UNITED STATES PATENT OFFICE.

MARTHA P. MARBACH AND FRANK G. MARBACH, OF LAKEWOOD, OHIO.

WASHING MACHINE.

Application filed July 31, 1923. Serial No. 654,923.

To all whom it may concern:

Be it known that we, MARTHA P. MARBACH and FRANK G. MARBACH, citizens of the United States, residing at Lakewood, in the county of Cuyahoga and State of Ohio, have invented certain new and useful Improvements in a Washing Machine, of which the following is a specification.

The present invention relates to an improvement in washing machines, and the general object of the invention is to provide a simple and effective plunger attachment for a tub or laundry tray wherewith to agitate the water and promote the washing of the goods therein. This attachment is also particularly constructed to be conveniently thrown back and out of the tub to give free access to the washing compartment when the device is not in operation. A compressible plunger or cup forming part of this attachment is also constructed to produce an efficient agitating and washing action with the application of a minimum of power, that is, the plunger embodies a valve adapted to permit the water to pass freely through the same upon a down stroke and then to be bodily lifted and cascaded over the goods upon the reverse or up stroke. There are other features of construction which embody other objects and yield certain advantages, and these are hereinafter more particularly shown and described in detail and pointed out in the claims.

In the accompanying drawings, Fig. 1 is a top view of a compartmented laundry tray or tub embodying this invention, the cover plate being partly broken away to disclose the valved plunger beneath the same.

Fig. 2 is a rear view of the tub and its attachments.

Fig. 3 is a vertical section transversely through the tub and the plunger, on line 3—3 of Fig. 1, showing the working parts in full lines in one operating position and in dotted lines in another.

Fig. 4 is a perspective view of the cover and the hinged supporting arm for the plunger.

Fig. 5 is a perspective view of the dash cup or plunger alone.

Fig. 6 is a cross section of the tub and its attachment parts, showing the cover and plunger in an elevated and retired position.

Fig. 7 is a horizontal section of the supporting frame for the tub and its power-transmitting parts on line 7—7 of Fig. 3.

Fig. 8 is a perspective view of the locking handle.

Figs. 9 and 10 are sectional and bottom views of a slightly modified form of dash cup or plunger.

As shown in the drawings the tub or laundry tray 2 is made of concrete and comprises a cross wall 3 at its middle to provide two washing compartments 4 and 5. However, the tub or tray may be constructed in various ways and of different materials and one or any number of compartments may be used without in any way affecting the present invention. The tub is also equipped with hot and cold water faucets 7 and 8, respectively, which are connected to separate water-supply pipes 9 and 10, respectively, extending horizontally at the rear of the tub, and one of these pipes is utilized to connect the washing attachment to the tub. The tub is also seated upon a skeleton angle-iron frame 11 having a platform 12 adapted to support an electric motor 14, a belt shifting device 15, and a gear casing 16, beneath the tub. The belt shifting device comprises a horizontal rod 17 mounted in bearings above platform 12 and having an operating handle 18 extending upwardly at one end of the tub, see Fig. 2, and an upright arm or finger 19 fixed to the inner end of rod 17 is adapted to engage a belt 20 extending from a pulley 21 on motor shaft 22 to a set of fixed and loose pulleys 23 and 24, respectively, upon a transverse shaft 25 journaled in gear casing 16. This casing is bolted to a base plate 26 which extends rearwardly beyond skeleton frame 11, and an adjusting thimble or screw 27 at the rear end of plate 26 (see Fig. 3) permits the gear casing 16 to be tilted slightly and aligned or trued in respect to the opposite bracket or bearing 28 for transverse shaft 25. A worm or pinion 29 on shaft 25 meshes with a worm gear 30 on a short shaft extending from casing 16, and a crank arm 31 on this short shaft is adapted to impart an oscillatory movement to a beam or lever 32 situated above the tub by means of a connecting rod 33 and tube 34, see Fig. 3. A cross pin 35 in rod 33 serves to rotate tube 34 but is free to slide in a longitudinal slot 36 therein, and a coiled compression spring 37 sleeved on rod 33 presses against the lower end of the tube and provides a yielding power-transmitting connection for oscilla-

105
110

tory lever 32 whereby when the oscillatory movement of the lever is checked or meets with considerable resistance at its plunger end the crank 31 may continue to revolve 5 without straining or breaking the operating parts or injuring the goods within the tub.

The oscillatory beam or lever 32 is provided with pivot trunnions 38 which are seated upon a pair of forked posts 39 extending upwardly from a cross bar 40 spanning the top of the tub or tray. Bar 40 is formed with diverging arms 41-41 at its rear end which are hinged or rotatably connected to the upper ends of a pair of clamping brackets 42-42 stationed at the rear of the tub and detachably secured to one of the water-supply pipes,—lower pipe 9 in this instance. The upper portion of each bracket 42 is relatively thin and lies closely against 20 the rear wall of the tub to permit upper pipe 10 to extend past the brackets toward the right end of the tub if a water supply connection is to be made from that end instead of from the opposite or left end as delineated in Fig. 2.

The front end of oscillatory lever 32 is bifurcated and slotted to loosely confine a pivot block or holder 43 through which the round stem 44 of a washing or agitating plunger 45 is adapted to extend, and a thumb screw 46 secures stem 44 adjustably within holder 43. The lower end of plunger stem 44 extends through a packed boss or bearing 47 at about the middle of bar 40 and the agitating plunger 45 is fixed to the lower end of this stem 44 and adapted to be reciprocated vertically within the tub when bar 40 spans the top thereof. Plunger 45 is of an elongated or rectangular shape 40 and dished or open at its bottom, and has slightly inclined or flaring side walls 48 and a substantially flat top 49. The top of the plunger is preferably slightly depressed between its border edges or else provided 45 with a rounded border bead or rib 50 to form a shallow water collecting basin 51 at its top. The middle top portion of the plunger is also preferably provided with a series of water escape openings 52 radially in respect 50 to its stem 44, and a flat round disk of rubber or leather 53 sleeved upon or fixed to the stem is adapted to cover and close these openings and function as a flap valve when the plunger moves upwardly. Upon a 55 downward stroke of the plunger part of the water beneath the plunger passes freely through openings 52 and circulates beneath the disk or valve. The water in the tub is thus not merely agitated but is also caused 60 to circulate from the sides of the tub to the center and upwardly through the plunger, when the plunger descends. Upon its reverse movement upwardly the water caught or collected on top of the plunger and valve 65 is lifted and cascaded in all directions from

the plunger toward the sides of the tub, and the flat depressed top of the plunger promotes this cascading effect and causes the water to throw outwardly a substantial distance beyond the border edges of the plunger. A rectangular or elongated form of plunger also serves to distribute the water effectively to all corners of a square or rectangular compartment, and division walls 54 may be used to divide the plunger into 70 separate middle and end chambers or pockets 55 and 56, respectively, the middle pocket alone having the water escape openings 52 if desired, see Figs. 9 and 10.

Hinged bar 40 is preferably ribbed longitudinally at its top to strengthen it and also to provide a seating channel lengthwise thereof for a supplementary fastening bar 55' having a slanting clamping flange or extension 56' and a loop-shaped handle 57 at 80 its outer end which may be shifted underneath and against the overhanging sloping front wall 36 of the tub when bar 40 is placed at rest upon the top edges of the tub. A locking screw 58 passes through a slot in handle bar 55' and engages main bar 40 in securing the said parts in immovable position upon the tub, but when these parts are unlocked the main bar, together with the plunger, may be raised and thrown back 85 into an upright inclined position above the rear wall of the tub substantially as shown in Fig. 6. However this cannot be readily accomplished unless oscillatory lever 32 is permitted to free itself from the forked posts 39 upon bar 40. It is for that reason that the trunnions 38 are seated in the open forked ends of said posts. On the other hand it is also desirable that when the bar and plunger are down and the plunger is 90 operating that the trunnions be held securely within the forked posts. Therefore a pair of hooks or catches 60 are pivotally mounted upon the outer sides of posts 39 to engage the projecting ends of trunnions 38 when the latter are seated within the forked ends of the posts, and in order that convenient locking and unlocking of the hooks or catches may be effected the supplemental bar 55' having handle 57 is divided 95 at its inner end to straddle the boss or bearing part 47 at the top of main bar 40 and to extend a notched extremity 61, beneath a depending finger 62 on each hook 60. Thus when handle 57 is pulled forward to unlock main bar 40 from the tub the catches or hooks 60 are thereby rotated sufficiently 100 to completely disengage the hooks from trunnions 38. The unlocked and disengaged position of parts is shown in Fig. 6, and the locked position of parts is illustrated in Fig. 3. When the operator has finished any given washing operation, or desires to inspect or remove any of the goods from the tub, it is a simple operation to stop 105 110 115 120 125 130

the motor by means of the belt-shifting device and then pull out handle 57 and raise the hinged bar to the inclined rest position shown in Fig. 6. Co-acting stop lugs or 5 shoulders 63 are also provided on brackets 42 and the hinged arms 41 to limit the rearwardly swinging movement of bar 40 carrying plunger 45, and a flat sheet-metal plate 64 secured to the bottom of bar 40 completely 10 covers the washing compartment when the bar and said cover plate is lowered and at rest upon the top of the tub. Agitation of the water and washing of the goods thus 15 takes place in a closed compartment, entrance to which is however conveniently accessible at all times, and from which compartment all operating parts may be quickly removed by merely lifting cover plate 64 through the medium of hinged bar 40 and 20 handle 57. Cover plate 64 is preferably made with a hinged section 65 to permit compartment 4 to be partly uncovered for inspection of the goods or operations within the tub when the main section or plate 64 25 is down upon the tray, and the position of the plunger within compartment 4 may also be regulated by a ring nut 66 having screw-threaded engagement with tube 34, thus, ring nut 66 provides an adjustable stop for 30 cross pin 35 in connecting rod 33 upon the downward movement of said rod. Adjustment of nut 66 longitudinally upon tube 34 places the plunger in different operating 35 positions relatively to the level of the water of the goods within compartment 4, and the tension on compression spring 37 may also be increased or decreased by such adjustment. Spring 37 permits the plunger to 40 yield under excess resistance on its down stroke, and the connecting rod and tube and pivoted lever provide flexible power connections adapted to permit the cover and plunger to swing freely above the tub.

What we claim is:

45 1. A washing machine, comprising a tub and a support therefor, a plunger having a supporting member hinged to a wall of the tub, an oscillatory lever for said plunger detachably connected with said supporting member, and means adapted to oscillate said lever mounted upon said tub support.

50 2. A washing machine, comprising a tub, a washing plunger and a hinged support therefor at the top of said tub, operating means for said plunger having separable connection with said hinged support, and a common locking device for said operating means and said hinged support.

55 60 3. A washing machine, comprising a tub, a reciprocable plunger for said tub, a support for said plunger hinged to the tub having a clamping device to fix the support upon

the tub, an operating lever for said plunger mounted upon said support, and locking means connected with said clamping device 65 adapted to secure said lever separably upon said support.

4. A washing machine, comprising a tub, a reciprocable plunger for said tub, a hinged member adapted to support said plunger 70 having posts, an oscillatory lever connected with said plunger having separable fulcrum engagement with said posts, and means adapted to oscillate said lever.

5. A washing machine, comprising a tub, 75 a hinged element above said tub, a plunger movably connected with said element, an oscillatory lever for said plunger, a slotted tube and a rod pinned thereto adapted to actuate said lever, a compression spring 80 sleeved upon said rod and engaging said tube, and crank and gear mechanism adapted to actuate said rod.

6. A washing machine, comprising a tub, 85 having a water supply pipe adjacent thereto and an agitating plunger for said tub having a support in hinged connection with said pipe.

7. A washing machine, comprising a tub having a water supply pipe connected thereto, a bracket fixed to said pipe, and an agitating plunger adapted to operate within 90 said tub having a support hinged to said bracket.

8. A washing machine, comprising a tub 95 having parallel water supply pipes mounted thereon, a clamping bracket adjustably affixed to one of said pipes, a bar hinged to said bracket affixed to one of said pipes, 100 a bar hinged to said bracket adapted to span the tub, and a reciprocable agitating plunger mounted upon said bar having power connections.

9. A washing machine, comprising a tub 105 and a dished plunger reciprocably mounted within the tub having a flat shallow depression and a series of openings in its top and a single valve member seated above said openings.

10. A washing machine, comprising a tub 110 having a reciprocable plunger therein, a base frame for said tub having a motor mounted thereon, and power connections between said motor and plunger embodying a shaft extending from said casing, a 115 bracket for said shaft mounted upon said base frame, and an adjusting screw for said gear casing adapted to facilitate alignment thereof and its shaft with the bracket on the main frame.

In testimony whereof we affix our signatures.

MARTHA P. MARBACH.
FRANK G. MARBACH.
